UNITED STATES PATENT OFFICE.

JOHN G. LYNN, OF CINCINNATI, OHIO, ASSIGNOR OF ONE-HALF TO
RICHARD WOOLLEY, JR., OF SAME PLACE.

SHOE-MAKER'S PINCHERS.

SPECIFICATION forming part of Letters Patent No. 315,430, dated April 7, 1885.

Application filed January 9, 1885. (No model.)

To all whom it may concern:

Be it known that I, JOHN G. LYNN, a citizen of the United States, and a resident of Cincinnati, in the county of Hamilton and State of Ohio, have invented a certain new and useful Improvement in Shoe-Maker's Tools, of which the following is a specification.

My invention relates to a combination-tool for shoe-makers' use. Its object is to provide a simple implement to do the work which ordinarily requires two or more tools, and thus save the expense of several tools and time required to handle them.

The invention consists in providing the ordinary shoe-maker's pinchers with a wedge-shaped fulcrum, which projects from one jaw of the pinchers, to enable the tool to be conveniently used in lasting the shank of a boot or shoe, thus taking the place of a shank-laster. The wedge-shaped point is also useful for removing tacks and ripping off a damaged upper, for which there is now no regular tool. It is also very convenient for removing "lifts" from heels, which work is now inconveniently performed by the awl.

In the accompanying drawings, Figure 1 is a side elevation of an ordinary shoe-maker's pinchers provided with my improvement. Fig. 2 is a perspective elevation of the same.

The lower jaw, A, with its fulcrum and hammer B, is constructed in the usual manner, as is also the upper jaw, C, except that its forward end is provided with the forward projection, D. I prefer to make this projection the full width of the upper jaw, and blunt-edged, as shown, so as to give a better bearing and be sufficiently pointed to be forced under the lift without being so sharp as to cut in lasting; but I do not desire to limit myself

to the exact form of the piece D shown, as it 40 is obvious different forms might be used for shank-lasting, so long as the piece projects in substantially the same direction from the upper jaw. It is also immaterial whether the wedge D be in one piece with the upper jaw 45 or made detachable from it. As the piece D is not in the way when the pinchers are used in the ordinary way, it is best in making new tools to make the wedge and upper jaw in one piece; but the wedge D may be made 50 separate, so as to be attached by any of the well-known methods to the pinchers now in common use.

In practice the toe and fore part of the boot or shoe are lasted with the common pinchers, and to make a good job of work a shank-laster is then employed to complete the lasting, as the common pinchers could only be used in a horizontal position, in which position the leather will be drawn up and from the last. With 60 my pinchers the toe and fore part are lasted, as usual. Then the pinchers are reversed and used in a vertical position. In this position the leather is drawn to and upon the last. Thus a much neater job of work can be done in 65 less time than with the tools now in common use.

What I claim is—

In a shoe-maker's tool, the combination, substantially as specified, of the jaw A and 70 fulcrum B with jaw C, having the fulcrum D projecting longitudinally forward from it, for the purpose set forth.

JOHN G. LYNN.
